United States Patent Office

Des. 225,279
Patented Nov. 28, 1972

225,279

ELECTROSTATIC COPYING MACHINE

Paul Matwey, Binghamton, N.Y., assignor to
GAF Corporation, New York, N.Y.

Filed Oct. 27, 1970, Ser. No. 25,681

Term of patent 14 years

Int. Cl. D16—04

U.S. Cl. D61—1

Fig. 1.

Fig. 4.

Fig. 2.

Fig. 3.

FIG. 1 is a front perspective view of an electrostatic copying machine showing my new design;

FIG. 2 is a front elevational view thereof;

FIG. 3 is a right side elevational view thereof;

FIG. 4 is a top plan view thereof.

The rear and left sides are plain and unornamented.

I claim:

The ornamental design for an electrostatic copying machine, substantially as shown and described.
